[57] **CLAIM**

The ornamental design of a display panel, as shown and described.

DESCRIPTION

FIG. 1 is a front elevational view of the embodiment of a display panel of the design according to the invention; FIG. 2 is a top plan view of the display panel of FIG. 1 (a back cover, which does not form part of the invention, is shown in phantom);

FIG. 3 is a bottom plan view of the display panel of FIG. 1 (a back cover, which does not form part of the invention, is shown in phantom);

FIG. 4 is a left side elevational view of the display panel of FIG. 1 (a back cover, which does not form part of the invention, is shown in phantom);

FIG. 5 is a right side elevational view of the display panel of FIG. 1 (a back cover, which does not form part of the invention, is shown in phantom); and,

FIG. 6 is an isometric projection of the display panel of FIG. 1 (a back cover, which does not form part of the invention, is shown in phantom).

The rear view of embodiment includes no ornamentality and, therefore, has been omitted from the drawings.
